United States Patent Office

Des. 211,614
Patented July 2, 1968

211,614

TRAFFIC SIGNAL

Edgar P. Warner, 99-12 65th Road,
Forest Hills, N.Y. 11375

Filed Aug. 11, 1967, Ser. No. 8,231

Term of patent 14 years

(Cl. D72—1)

FIG.1

FIG.2

FIG.3

FIG.4

FIG. 1 is a perspective view of a traffic signal showing my new design;

FIG. 2 is a side elevational view of the side opposite the left front side as seen in FIG. 1;

FIG. 3 is a side elevational view of the side opposite the right front side as seen in FIG. 1; and

FIG. 4 is a sectional view taken on line 4-4 of FIG. 2.
The shading is representative of the colors red, green and yellow.

I claim:

The ornamental design for a traffic signal, as shown and described.
